US00D456351S

(12) **United States Design Patent** (10) Patent No.: **US D456,351 S**
Yoneda (45) Date of Patent: **** Apr. 30, 2002**

(54) **COMBINED INFRARED RAY EMITTER AND CHARGER FOR HEADPHONE**

Catalog "Headphone/Active speaker system", p. 19, Sony Corporation, Jul. 2000.

(75) Inventor: **Naofumi Yoneda**, Tokyo (JP)

* cited by examiner

(73) Assignee: **Sony Corporation**, Tokyo (JP)

Primary Examiner—Joel Sincavage
(74) Attorney, Agent, or Firm—Rader, Fishman & Grauer, PLLC

(**) Term: **14 Years**

(57) **CLAIM**

(21) Appl. No.: **29/144,206**

The ornamental design for a combined infrared ray emitter and charger for headphone, as shown and described.

(22) Filed: **Jun. 29, 2001**

DESCRIPTION

(51) LOC (7) Cl. **13-02**
(52) U.S. Cl. **D13/108; D14/224**
(58) Field of Search D13/107, 108; D14/253, 155, 224; 320/107-115

FIG. 1 is a perspective view of a combined infrared ray emitter and charger for headphone showing my new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof; and
FIG. 7 is a bottom plan view thereof.
FIG. 8 is another embodiment of a combined infrared ray emitter and charger for headphone showing my new design;
FIG. 9 is a front elevational view thereof;
FIG. 10 is a rear elevational view thereof;
FIG. 11 is a left side elevational view thereof;
FIG. 12 is a right side elevational view thereof;
FIG. 13 is a top plan view thereof; and,
FIG. 14 is a bottom plan view thereof.
